UNITED STATES PATENT OFFICE.

HERMAN G. C. PAULSEN, OF NEW YORK, N. Y.

IMPROVEMENT IN REFINING SUGAR.

Specification forming part of Letters Patent No. 37,824, dated March 3, 1863.

To all whom it may concern:

Be it known that I, HERMAN G. C. PAULSEN, of New York, county and State of New York, have invented a new and Improved Mode of Purifying Refined Crystallized Sugar of its Mother-Liquor or Sirup; and I do hereby declare that the following is a full and exact description thereof.

The nature of my invention consists in applying to the refined crystallized sugar a bath of alcohol vapors of a low temperature, and effecting a condensation of said vapors on their entering and progressively penetrating the porous mass of sugar-crystals by having previously cooled the mass of sugar by injection of cold alcohol or a blast of cold air through it, thereby leaching or draining out the sirup suspended by capillary attraction between the crystals of sugar.

To enable others skilled in the art to make and use my invention, I will proceed to describe its operation.

The vessel A, in which the sugar has to be crystallized, must be a closed vessel strong enough to sustain a vacuum. To this crystallization-vessel A must be attached a surface-condenser, B, a receiver of condensed liquor, H, and an air-pump, C, for the purpose of having the sugar to be acted on in a vacuum to permit the vapors of a low temperature to exist and to act as intended; but this attachment must be at the lowest part of the bottom of said crystallization-vessel at a, for the purpose of drawing the vapors and the liquor condensed in the sugar by the action of the air-pump C and condenser B through the mass of crystallized sugar in A. To the crystallization-vessel A is also attached or connected by means of pipes and other suitable fixtures a second vessel, D, the vapor-boiler containing the alcohol, from which the vapors are to be raised, and which vapor-boiler must be provided with all requisite fixtures of filling and feeding thereinto the alcohol, as well as to heat up to that temperature required for raising the vapors. This communication of the vapor-boiler must be with the upper part or the top of the crystallization-vessel at b, for the purpose of entering therein the vapors above the surface of the sugar. The crystallization-vessel A is also connected with other vessels or set of vessels, d d d, so arranged as

to receive the flowing-out mother-liquor or sirup and the alcohol used for washing out and cooling the sugar. The vessel A must also be connected with another vessel, E, containing the cold alcohol, and with an air-force pump, F. The alcohol from which the vapors are to be raised or that used for cooling the sugar is of eighty per cent., or above this, and the temperature of the vapors between 100° and 150° Fahrenheit.

The mode of operation is as follows: The crystallization of the sugar in the vessel A having been completed by cooling down to about 100° or 90° Fahrenheit, the mother-liquor is first blown out by a blast of cold air produced by the action of the air-force pump F. Said mother-liquor, flowing out at a, is received or enters the first of the vessels d. The communication of the crystallization-vessel A with all the other vessels is now opened, except with the reservoir of cold alcohol E, and that with the air-force pump F is closed by means of the cock O. The required vacuum corresponding to the temperature of the vapors to be applied is formed by the action of the air-pump C and condenser B, and at the same time the alcohol in the vapor-boiler D is heated up to the temperature of the required vapors. This starts directly the flowing out or draining at a of the remaining mother-liquor out of the sugar, which sirup is also received by the vessel d. If the vacuum is of twenty-six inches, the temperature of the vapor-boiler will be about 110° to 115° Fahrenheit, and by raising the vacuum to twenty-eight inches, but keeping the alcohol in the vapor-boiler at 110° to 115° Fahrenheit, the vapors produce a small pressure on the surface of the draining-out mother-liquor, assisting thereby the penetration of the vapors into and through the porous mass of sugar or driving the mother-liquor out. At the same time, the sugar being colder than the vapors, part of the vapors in penetrating downward, drawn by the action of the pump C and condenser B through the mass of sugar, condense, and in the act of condensing dissolve and extract the small quantity of sirup which was left hanging by capillary attraction among the small sugar-crystals by expelling said mother-liquor at the commencement of the operation. This vapor bath having been continued till the

hole crystallization-vessel A, with the sugar it contains, has been heated or warmed up by means of the entering vapors to the same temperature of said vapors, the ingress of vapors is stopped by closing the cock h, and a sufficient quantity of cold alcohol out of the vessel E is run into the crystallization-vessel A to cool down on penetrating the whole mass of sugar to a temperature sufficiently low to effect the condensation of said vapors, and at the same time washing out the sirup which was dissolved or extracted by the condensing vapors. All the vapors which pass through the sugar are condensed in the condenser B, and the condensed alcohol is collected in the receiver H. After this the same operation is to

be repeated, commencing by blowing out the alcohol with a blast of cold air followed by vapor bath and cold alcohol. Two applications of the vapor bath are generally sufficient to effect the desired purification.

What I claim as my invention, and desire to secure by Letters Patent, is—

The application of alcohol vapors of the temperature and for the purpose as herein stated to refine crystallized sugar.

New York, October 24, 1860.
